UNITED STATES PATENT OFFICE.

ALBERT E. CALDWELL, OF ERIE, PENNSYLVANIA, ASSIGNOR TO CONTINENTAL RUBBER WORKS, OF ERIE, PENNSYLVANIA, A CORPORATION OF PENNSYLVANIA.

ARMORED HOSE.

Application filed December 10, 1923. Serial No. 679,615.

This invention is designed to form an effective armor for tubes.

The invention is illustrated in the accompanying drawings as follows:—

5 Fig. 1 shows a side elevation, partly in section.

Fig. 2 a side elevation with part of the armor in section with the tube flexed.

The tube is a flexible tube. As shown it 10 is made up of an inner wall of rubber 1, a layer of fabric 2, and an outer wall of rubber 3. This is of ordinary construction.

The armor is made up of alternate flat and 15 curved wires 4 and 5, the curved wire being concavo-convex in cross section, the concave side being next the wall 3 with the edges rounded so that they may indent without cutting the wall of the rubber 3. The flat wire preferably overlaps slightly the concave portion of the curved surface wire and 20 is carried into the curved portion so as to be maintained accurately with relation to the curved wires and make an approximately closed armored shield.

25 When the tube is flexed, as shown in Fig. 2, the flat wire at the inner side of the bend rides up on the curved portions of the wire and this draws the flat wire down to the tube on the outside of the bend, the curved 30 wires slightly separating due to the expansion of the tube at the outer side and being brought closer together at the inner side of the bend.

By making the curved wire concave on its 35 inner surface the edges locate the wire with relation to the wall and thus hold it in place so as to obviate any tendency to uncover portions of the tube and at the same time affords a space for the rubber of the tube to 40 flow as it is compressed slightly at the inner side of the bend. Further the alternate square edges of the flat wire do not tend to catch material to so great an extent as wire having an undercut edge.

45 What I claim as new is:—

1. In an armored hose, the combination 50 of a flexible tube; and an armor winding comprising alternate wires coiled spirally with the succeeding coils of each wire spaced apart, one wire having both its inner and outer surfaces flat and the other having in cross section its outer surface convex, the flat wire bridging the space between and the inner surface lapping onto the coils of the 55 wire having its outer surface convex.

2. In an armored hose, the combination of a flexible tube; and an armor winding comprising alternate wires with the succeeding coils of each wire spaced apart, one wire having both its inner and outer surfaces flat 60 and the other having in cross section its outer surface convex and its inner surface concave, the flat wire bridging the space between and lapping onto the coils of the wire having its outer surface convex.

3. In an armored hose, the combination of a flexible tube; and an armor winding 65 comprising alternate wires coiled spirally with the succeeding coils of each wire spaced apart, one wire having both its inner and outer surfaces flat and the other having in cross section its outer surface convex, the inner diameter of the flat wire being greater 70 than the inner diameter of the curved wire, the flat wire bridging the space between and the inner surface lapping onto the coils of the wire having its outer surface convex.

4. In an armored hose, the combination of a flexible tube; and an armor winding 75 comprising alternate wires with the succeeding coils of each wire spaced apart, one wire having both its inner and outer surfaces flat and the other having in cross section its outer surface convex, the inner diameter of 80 the flat wire being greater than the inner diameter of the curved wire but of less diameter than the outside diameter of the curved wire, and flat wire bridging the space between and the inner surface overlapping the edges of the curved wire.

5. In an armored hose, the combination of a flexible tube; and an armor winding 85 comprising alternate wires with the succeeding coils of each wire spaced apart, one wire having both its inner and outer surfaces flat and the other having in cross section its outer surface convex, the inner diameter of the flat wire being greater than the inner diameter of the curved wire but of less diameter 90 than the outside diameter of the curved wire and bridging the space between and overlapping the edges of the curved wire, the relation of the wires permitting the drawing of the flat wire into contact with the tube at the outside of the tube bend as the tube is 95 flexed and the forcing of the flat wire upwardly along the outer surface of the curved wire at the inside of the bend.

6. In an armored hose, the combination 100 of a flexible tube; and an armor winding 105 of a flexible tube; and an armor winding 110

comprising alternate wires with the succeeding coils of each wire spaced apart, one wire having both its inner and outer surfaces flat and the other having in cross section its 5 outer surface convex and its inner surface concave, the inner diameter of the flat wire being greater than the inner diameter of the

curved wire but less than the outer diameter of the curved wire and bridging the space between and overlapping the curved wire. 10

In testimony whereof I have hereunto set my hand.

ALBERT E. CALDWELL.
